COMBINATION SOAP, TOOTHBRUSH, WATER-GLASS AND TOOTHPASTE HOLDER

Carlos A. Palacios, 9750 Ramo Court, Santee, Calif.

Filed Mar. 25, 1963, Ser. No. 74,108

Term of patent 3½ years

(Cl. D4—3)

FIG. 1

FIG. 3

FIG. 1 is a front elevational view of a combination soap, toothbrush, waterglass and toothpaste holder, showing my new design;

FIG. 2 is a top plan view thereof;

FIG. 3 is a rear perspective view thereof.

I claim:

The ornamental design for a combination soap, toothbrush, waterglass and toothpaste holder, as shown.
